UNITED STATES PATENT OFFICE

PAUL BRADFORD THOMPSON, OF RICHMOND, VIRGINIA, ASSIGNOR TO NATIONAL PEPSI-COLA CORPORATION, OF RICHMOND, VIRGINIA, A CORPORATION OF VIRGINIA

DESIGN FOR A BOTTLE FOR SOFT DRINKS

Application filed August 20, 1929. Serial No. 32,462. Term of patent 14 years.

To all whom it may concern:

Be it known that I, PAUL BRADFORD THOMPSON, a citizen of the United States, residing at Richmond, in the county of Henrico and State of Virginia, have invented a new, original, and ornamental Design for a Bottle for Soft Drinks, of which the following is a specification, reference being had to the accompanying drawing, forming part thereof.

The figure is a front elevational view of a bottle showing my new design. The rectangular panel shown appears on the front side only.

I claim:

The ornamental design for a bottle for soft drinks as shown and described.

In testimony whereof I have hereunto set my hand on this 15th day of August, 1929.

PAUL BRADFORD THOMPSON.
